UNITED STATES PATENT OFFICE.

HENRY G. O'BRIEN, OF WARREN, OHIO,

PILING AND TRANSFER APPARATUS.

1,331,208.

Specification of Letters Patent. Patented Feb. 17, 1920.

Application filed August 26, 1918. Serial No. 251,447.

To all whom it may concern:

Be it known that I, HENRY G. O'BRIEN, residing at Warren, in the county of Trumbull and State of Ohio, a citizen of the 5 United States, have invented or discovered certain new and useful Improvements in Piling and Transfer Apparatus, of which improvements the following is a specification.

10 The object of my invention is to provide a piling apparatus for rolling mills, whereby blanks may be continuously received from a roll table or other conveyer, evenly piled on top of each other, and quickly removed 15 after having been piled. A further object is to provide an apparatus such as described and which may be adjusted to pile blanks of different widths and lengths.

15 In the accompanying sheets of drawings, which form part of my specification, I have illustrated an embodiment of my invention. Figure 1 is a plan view showing the general arrangement of the piling apparatus associated with a roll table conveyer; Figs. 2 20 and 3 are sectional elevations taken, respectively, on the lines II-II and III-III, Fig. 1; Fig. 4 a plan view of a portion of the apparatus shown in Fig. 3; and Fig. 5 a detail sectional view taken on the line V-V, 25 Fig. 3.

30 In the practice of my invention, I provide, at the end of a conveyer, a horizontally movable table adapted to receive elongated blanks conveyed by the table. Above the 35 table there are arranged a pair of laterally-spaced plates lying in vertical planes parallel to the general line of extent of the conveyer, the arrangement being such that the conveyer may pass blanks, one after the 40 other, upon the platform between the plates, which plates cause the blanks to be arranged in an even pile. Means are provided for moving the plate vertically to permit the transfer table to move horizontally after 45 the completion of each pile of blanks. Preferably the horizontally movable table is in the form of a transfer table provided with a pair of tracks adapted to support trucks in alignment with or parallel to the blank conveyer, and a plurality of stub end tracks are 50 arranged at each side of the conveyer so that, while one truck is being loaded, a previously loaded truck may be removed from the transfer table and replaced by an empty truck to 55 be subsequently loaded when the transfer table is again moved.

My invention, while unlimited to its association with any particular type of conveyer or to a conveyer for any particular purpose, it is illustrated in connection with 60 a live roll table comprising a plurality of rolls 1 driven by means of a motor 2 and the gears and shafts diagrammatically indicated in Fig. 1. Lying in the path of the roll table, there is a shear 63 adapted to cut 65 elongate blanks of sheet metal into required lengths.

As already stated, a piler is arranged at the end of the roll table, and a transfer table below such piler so that the successively 70 sheared blanks, as they are continuously passed along the roll table from the shear, may be properly piled and quickly removed from the vicinity of the shear. The piler comprises a pair of vertically disposed plates 75 3 having serrated lower edges adapted to rest upon piling rails 4 carried by a truck 5, which truck is movable, by means of a transfer table presently to be described, to and from a position at the end of the roll table. 80 The piler plates are laterally adjustable to receive cut blanks of different widths, and vertically movable to permit a loaded truck to be moved laterally below their lower edges. As shown herein, pair of arms 6 and 85 6^a are attached to the ends of the plates 3. To such arms there are secured interiorly threaded sleeves or bushings 7 which receive the ends of oppositely threaded screws 8 and 8^a. For causing the two screws to turn 90 simultaneously, they are provided with sprockets 9 connected by a chain 10, and to each screw a hand wheel 11 is attached. That the plates may be held in vertical alignment, they are connected to each other by 95 two pairs of toggles comprising laterally projecting links 12 pivoted to the arms 6 and 6^a, and vertical links 13 pivoted to the outer ends of the links 12, as indicated in Figs. 4 and 5.

100 For moving the piler plates vertically, the outer ends of the screws 8 and 8^a are suspended from yokes 14 and 15 pivotally mounted on supports or standards 16 and 17, respectively, the yoke 15 being connected 105 to the screw 8^a by means of a link 18 to permit a slight longitudinal movement of the plates 3 when the yokes swing to move such plates vertically. Each yoke is provided with a laterally projecting arm 19, 110 which arms are connected to each other by rod 20, so that the two yokes may swing in

unison. The piler may be counterweighted by means of a weight 21 adjustably carried by an arm 22 secured to the yoke 15.

As will be seen in Figs. 2 and 3, the general arrangement of the piling apparatus is such that the supporting rails 4 of the truck 5 are below the plane of the roll table. To feed the sheared blanks beyond the end of the roll table and upon the truck, there may 10 be provided a pair of pinch rolls 23 adapted to be driven by a shaft 24 which drives the roll 1 of the roll table. The pinch rolls will ordinarily be driven at a speed sufficient to cause a blank, after it passes beyond their 15 engagement, to slide upon the plate beneath it a sufficient distance to clear the pinch rolls and their housing. That the ends of the plates forming a pile may be arranged evenly, a suitable adjustable stop 25 may 20 be arranged between the piler plates 3, it being understood that the position of such stop with reference to the pinch rolls 23 or to the end of the piler plates 3 will be determined by the lengths of the blanks being 25 piled.

As already stated, the truck 5 rests upon and is movable by a transfer table. As seen in Figs. 2 and 3 the transfer table 26 rests within a shallow pit 27 upon a track 28 extending at right angles to the roll table. The transfer table is adapted to be moved from one to the other end of the pit, and hence from one side to the other of the roll table, by means of a motor 29, the driving 30 connections between such motor and transfer table including a shaft 30, beveled pinions 31 and 32, countershaft 33, pinion 34, and rack 35 secured to the bottom of the transfer table. On top of the transfer table 35 there are two truck-supporting tracks 36 and 37, as seen particularly in Fig. 2, and leading from the opposite side of both ends of the pit 27, and parallel with the general line of extent of the roll table, there are 40 stub-end tracks 38, 39, 40 and 41. Thus, while one truck is being loaded, a previously loaded truck may be removed from the transfer table and an empty truck placed on such table in readiness to be moved to loading 45 position. It will be seen that the arrangement of tracks lends itself to the rapid piling of blanks and their quick removal from the vicinity of the shear.

In the operation of my invention, the 50 piler plates 3 are first adjusted laterally to positions depending upon the width of blanks to be piled. This adjustment is effected by the rotation of one or the other of the hand wheels 11, which causes the two 55 screws 8 and 8^a to turn simultaneously. Also, the adjustable stop 25 may be secured to the piler plates 3 at the proper interval from the receiving end of such plates to cause the blanks to be arranged evenly at 60 65 their ends.

With an unloaded truck 5 beneath the lower edges of the piler plates 3, the blanks to be piled may be fed one after the other upon the truck until the pile rises to a height approximately level with the meeting 70 plane of the pinch rolls 23. The inner ends of the yokes 14 and 15 are then raised to cause the piler plates to be lifted above the top of the pile, after which the motor 29 is operated to move the transfer table to one 75 end or the other of the pit 27. If the transfer table is in the position indicated in Fig. 1, it will be moved toward the upper end of the pit so that the track 37 on such table will be in alignment with the tracks 38 and 80 49. In such position the loaded truck may be removed, for example on the track 38, and an unloaded truck be moved from the track 40 and upon the track 37 of the transfer table. In this position of the table an 85 unloaded truck previously received from either the track 39 or 41 is in a position beneath the piler plates 43 to have a pile of blanks placed thereon. Thus, by moving the transfer table alternately from one end 90 of the pit to the other as the piles are successively formed on the trucks, the loaded trucks may be quickly removed from the piling position, and a practically uninterrupted stream of blanks may be properly 95 piled and disposed of.

According to the provisions of the patent statutes, I have described the principle and operation of my invention together with the apparatus which I now consider to represent the best embodiment thereof. However, I desire to have it understood that, within the scope of the appended claims, my invention may be practised with other forms of apparatus than that particularly shown 105 and described herein.

I claim as my invention:

1. In a piling apparatus, the combination of a horizontally movable table, a pair of laterally-spaced vertically-movable plates lying in vertical planes above said table, oppositely threaded screws engaging said plates at their opposite ends, and means for turning said screws simultaneously to effect a lateral adjustment of said plates. 110

2. In a piling apparatus, the combination of a horizontally movable table, a pair of laterally-spaced vertically-movable plates lying in vertical planes above said table, an oppositely threaded screw engaging said plates at each end thereof and rotatable to effect a lateral adjustment of said plates, and means interconnecting said plates for holding them in parallel alignment in their various laterally adjusted positions. 115

3. In a piling apparatus, the combination of a horizontally movable table, a pair of laterally-spaced plates lying in vertical planes above said table, a pivotally mounted arm at each end of said plates, means for 120 125 130

suspending said plates from said arms, and means for causing said arms to simultaneously turn on their pivot axes to effect vertical movements of said plates.

- 5 4. In a piling apparatus, the combination of a pair of laterally-spaced vertically-disposed plates, an oppositely threaded screw engaging said plates at each end thereof and rotatable to effect a lateral adjustment 10 of said plates, a pivotally mounted yoke at each end of said plates, pivotal connections

between the ends of said yokes and the outer ends of said screws, and means for causing said yokes to simultaneously turn on their pivot axes to effect vertical movement of said 15 plates.

In testimony whereof, I have hereunto set my hand.

HENRY G. O'BRIEN.
